UNITARY ROENTGEN APPARATUS

Kurt Bischoff, Alterlangen, near Erlangen, Carl Niemann, Buckenhof, near Erlangen, and Hans Wünsch, Erlangen, Germany, assignors to the firm Siemens-Reiniger-Werke Aktiengesellschaft, Berlin, Germany

Application August 25, 1936, Serial No. 97,774
In Germany August 26, 1935

5 Claims. (Cl. 250—34)

Our invention relates to Roentgen apparatus and is more specifically concerned with a novel and improved unitary structure wherein the Roentgen tube, the high tension transformer and the heating transformer, which is spaced therefrom and connected to high tension, are provided in a common housing and wherein the secondary winding of these separately placed and spaced transformers are united by a common insulating means to form a unitary and common structure.

A brief review of the reasoning underlying our invention with reference to the prior art is rendered below so that its various objects and advantages will be readily understood.

It is the aim in structures such as noted above, namely, in Roentgen apparatus wherein the Roentgen tube, the high tension transformer and also the heating transformer connected to high tension are provided in a common housing, to keep the weight and the dimensions of the apparatus as small as possible. In order to realize this aim, the secondary winding of the high tension transformer is provided with an insulating means, e. g., a suitable bandage or taping, and the conductor means leading from the high tension transformer to the Roentgen tube, and in certain instances parts of the tube, are also insulated against the grounded wall of the housing by an insulating provision which may be a bandage consisting of paper tape.

It may be mentioned at this point that the terms "insulating bandage" or "insulating tape or taping" and equivalent language, as used herein, are intended to convey insulating means wrapped around or provided on the respective parts in a suitable manner so as to form thereon an insulating layer or layers or an insulating covering of a sort which is suitable for the purpose in view. These terms are, therefore, not used to indicate undue limitations. In their broadest sense they should be construed simply as denoting "insulating means", regardless of the specific material of which this means consists and the manner in which it is applied. Paper is mentioned herein for an insulating material, but other materials may be used if desired.

The heating transformer is generally accommodated in such apparatus by disposing the heating winding directly upon the iron core of the high tension transformer. This is, however, impossible, for example, in apparatus of considerable output, wherein a separate regulation of the Roentgen tube tension and current is required. The placing of a separate heating trans-

former wherein the ring-like secondary winding is taped and the iron core grounded in usual manner causes difficulties because one pole of the high tension transformer must be electrically connected with the heating winding. This connection as such would have to be taped also.

According to the invention, the resulting difficulties, as intimated above, can be greatly reduced and the taping can be considerably simplified by connecting through a common insulating bandage or tape the secondary winding of the heating transformer, and at least that part of its iron core surrounded thereby, with the secondary winding of the separately disposed high tension transformer to form a unitary structure therewith. Inasmuch as the high tension-carrying taped part of the heating transformer forms then a unit with the secondary winding of the high tension transformer through the common taping, we obtain the same advantage that results in apparatus wherein the heating winding is provided directly upon the iron core of the high tension transformer. The Roentgen tube tension and current can also be separately regulated.

The invention will be better understood from the detailed description which is rendered below with reference to the accompanying drawing, wherein

Fig. 1 shows one embodiment of our invention in schematic representation; and

Fig. 2 illustrates a modification.

Like parts are designated by like reference numerals throughout the drawing.

Referring, now, to Fig. 1, numeral 1 indicates the grounded housing or casing containing the Roentgen tube 2 with its anode grounded as shown, the high tension transformer with its primary winding 3, secondary winding 4 and the iron core 5. The secondary winding 4 is insulated by means of paper taping 6 which also surrounds the conductor means 7 leading to the Roentgen tube 2. The secondary winding 8 of the separately placed open core heating transformer is included in the common taping 6 together with its iron core 9 which is electrically connected with the secondary winding 8. The primary winding 10 of the heating transformer is slipped over the taped part of the structure. If required, the iron core 9 may be continued outside of the taping, resulting in a heating transformer with an almost closed iron core.

In the embodiment shown in Fig. 2 the taped part of the heating transformer forms a protuberance on the common insulating taping 6.

in such a manner that the primary winding 10 of the heating transformer can be directly slipped into position upon the tapered part of the structure, from the outside thereof. Other parts in 5 Fig. 2 correspond to like parts discussed in connection with Fig. 1.

It will be seen from the foregoing that we have provided a structure in accordance with our invention wherein the high tension transformer is separately disposed at a distance from 10 or is spaced from the heating transformer while both are disposed in a common housing, as shown. The secondary winding of the high tension transformer and the secondary winding 15 of the heating transformer are united by a common insulating means to form a unit. A separate adjustment or independent adjustment or regulation of the high tension and of the tube current, respectively, is thus possible.

20 Attention is called to the fact that we have shown only the relevant details of the apparatus for the sake of convenience and simplicity of description. It is understood, of course, that matter known in connection with such apparatus, but for the noted reasons omitted herein, is considered to be part of the disclosure.

Specific embodiments have been shown in order to teach others how the invention may be used in practice. However changes and 30 modifications are possible within the scope and spirit of the invention, and we have therefore particularly defined in the following claims what is considered new and desired to have protected by Letters Patent of the United States.

35 We claim:

1. In a Roentgen apparatus including a Roentgen tube of the heated cathode type and a high tension transformer, the combination of a separate heating transformer including a core and a secondary winding thereon, a high tension conductor leading from one terminal of the secondary winding of said high tension transformer to one terminal of the secondary winding of said heating transformer, heating conductors leading 40 from the two terminals of the secondary winding of said heating transformer to the cathode of said tube, a continuous covering of fibrous insulating material applied in the form of a tape wrapping or bandage and covering the secondary winding of the high tension transformer, the 45 said high tension conductor, the secondary winding and core of said heating transformer, and the said heating conductors as far at least as the point where they enter said tube, and a primary winding for said heating transformer surrounding said insulating covering at the point where the latter encloses the secondary winding and core of said heating transformer.

2. In a Roentgen apparatus including a Roentgen tube of the heated cathode type and a high tension transformer, the combination of a core and secondary winding for a heating transformer positioned at a point between said tube and high tension transformer, conductors 60 extending from the terminals of said secondary winding to the cathode of said tube, a conductor

extending from the secondary winding of said high tension transformer to one of said first mentioned conductors, a continuous covering of insulating material enclosing all said conductors, said covering including a projecting branch portion 5 which encloses the said core and secondary winding of said heating transformer, and a primary winding for said heating transformer surrounding the said branch of the covering at the point where it encloses the said core and 10 secondary winding.

3. In a Roentgen apparatus including a Roentgen tube of the heated cathode type and a high tension transformer, the combination of a heating transformer including a core and a secondary winding, conductors for connecting the secondary windings of said transformers with the cathode of said tube, a continuous covering of insulating material enclosing both secondary windings and said conductors, and 20 a ring-shaped primary winding for said heating transformer adapted to be positioned outside the said covering where it encloses the core and secondary winding of the heating transformer, said primary winding being of such dimensions 25 that it cannot be slipped over the tube or the high tension transformer and the said covering having a projecting branch portion in which the said core and secondary winding are located, whereby the said primary winding can be brought 30 into the proper relation to such parts by slipping it over said projecting branch portion.

4. In a Roentgen apparatus which includes a Roentgen tube of the heated cathode type and a high tension transformer, the combination of 35 a core and secondary winding of a heating transformer, conductors extending from said winding to the cathode of said tube, a continuous wrapping of insulating material forming a covering for the said core and secondary winding and 40 all portions of said conductors between the said winding and tube, a conductor connecting said high tension transformer with said secondary winding and also enclosed in said covering, and a primary winding for said heating transformer 45 surrounding the said covering at the point where it encloses the said core and secondary winding.

5. In a Roentgen apparatus which includes a Roentgen tube of the heated cathode type and a high tension transformer, the combination of 50 a core and secondary winding of a heating transformer, conductors extending from said winding to the cathode of said tube, a conductor extending from said high tension transformer to one of said first mentioned conductors, a covering 55 of insulating material for said conductors, said covering comprising a continuous wrapping of tape material and including an enlarged offset portion which encloses said core and secondary winding, and a removable primary winding 60 surrounding the said enlarged portion of said covering.
